Primary Examiner — Sheryl Lane*Assistant Examiner* — Aula Soroush(74) *Attorney, Agent, or Firm* — Global IP Counselors, LLP(57) **CLAIM**

The ornamental design for a doghouse, as shown and described.

DESCRIPTION

FIG. 1 is a front perspective view of a doghouse showing our new design;

FIG. 2 is a rear perspective view of a doghouse thereof;

FIG. 3 is a top view thereof;

FIG. 4 is a bottom view thereof;

FIG. 5 is a right side elevation view thereof;

FIG. 6 is a left side elevation view thereof;

FIG. 7 is a front elevation view thereof; and,

FIG. 8 is a rear elevation view thereof.

The broken lines in the drawings illustrate portions of the doghouse that form no part of the claimed design.
